UNITED STATES PATENT OFFICE.

ARTHUR WILSON BAKER, OF DANBURY, CONNECTICUT.

OUTLET-BOX.

1,220,168.

Specification of Letters Patent.

Patented Mar. 27, 1917.

Application filed February 19, 1915. Serial No. 9,316.

To all whom it may concern:

Be it known that I, ARTHUR WILSON BAKER, a citizen of the United States, residing at Danbury, in the county of Fairfield and State of Connecticut, have invented certain new and useful Improvements in Outlet-Boxes, of which the following is a specification.

My invention relates to electrical fittings, and more particularly to that class of fittings known in the art as outlet boxes, and the primary object of my invention is to provide an outlet box which is simple in construction, strong, durable and cheap to manufacture.

Another object of my invention is to provide suitable means for detachably connecting electric conduits of any desired type to the outlet box at the various points of distribution as is common in the art, the salient feature of my invention residing in the peculiar fastening means and a new and novel plug or closure.

A still further object of my invention is to provide an outlet box which will be capable of connection with any of the many different types of electric conduits, merely by the provision of removable bushings secured in the manner hereinafter set forth in detail.

With the above and other objects in view my invention resides preferably in the construction, combination, and arrangement of parts as hereinafter set forth in the specification and illustrated in the accompanying drawings, in which—

Figure 1 is a top plan view of an outlet box including the preferred embodiment of my invention.

Fig. 2 is a longitudinal sectional view therethrough.

Fig. 3 is a vertical sectional view of one of the nipples employed in the preferred embodiment of my invention.

Fig. 4 is a side elevation of one of the bushings.

Fig. 5 is a plan view of one of the closures.

Similar reference characters indicate similar parts throughout the various views of the drawings.

Referring more particularly to the drawings in which the preferred embodiment of my invention is illustrated I provide an outlet box indicated generally by the numeral 1 and having a plurality of screw

threaded apertures 2, 3 and 4 in the side, end, and bottom walls, respectively, of said outlet box. Closures in the form of peripherally threaded disks 5 are provided receivable in the threaded apertures 2, 3 or 4 as so desired, each of the disks 5 having a recess 6 in one face thereof for reception of a screw driver or the like employed for facilitating insertion and removal of the disks. When the device is manufactured, it is provided with these closures, and as convenience allows, one or more of these disk closures 5 are removable to allow of connection to the outlet box or electric conduit of any of the usual forms.

I provide an improved connecting means which comprises in this instance a tubular nipple 7 having the central bore thereof threaded as shown at 8 and 9, the portions 75 8 and 9 of said threaded bore being slightly at variance in diameter for a purpose which will hereinafter be set forth. Tubular bushings 10 are provided having external screw threads 11, preferably for threaded engagement with any one of the apertures 2, 3 or 4, the said bushings 10 being preferably carried by the nipples 7, the former being in engagement with the threads 9. It will be noted from Figs. 2 and 3 that shoulders 12 85 are provided on the interior of the nipples 7, which limits inward movement of the bushings 10, so that a portion of the bushings 10 may extend beyond the terminals of the nipples 7 for engagement with the 90 threaded apertures as shown to advantage in Fig. 2 at 13. Any desired form of electric conduit may be threaded into the threads 8 of the nipples 7, I not desiring to limit myself to any particular type of electric conduit, and have therefore not shown any in the drawing. Any number of the apertures 2, 3 and 4 may be provided so as to increase the number of conduits which may be connected to the outlet box, and the shape of 95 the outlet box need not necessarily be as illustrated in the drawing. I desire to lay particular stress upon the peculiar connecting means which facilitates the connection of any number of different sizes of conduits 100 to the nipple 7, since the threaded portions 8 may be varied according to the requirements, different nipples being provided with each, it being kept in mind that the threaded portions 9 are always of a like size, so that 110 the same sized bushings may be used in each instance. Armored cable may be as readily

attached as ordinary iron piping and it will thus be seen that I have provided a connecting means which is simple in construction, and one which has a wide range of use.

5 It will be noted in Fig. 1 that one side of the outlet box has been left open, and a plurality of lugs 14 are provided on the inner walls thereof, the said lugs 14 being apertured as indicated at 15 for securement thereon of a suitable cover.

10 The apertures which are not being utilized can be closed by the disks 5, which disks may be removed for the connection of additional conduits. In some instances it may be found

15 desirable to bolt, or otherwise secure the outlet box 1 to a wall or the like, and to facilitate this, I have provided a modified form of disk which is designated 16 and is provided with a centrally located aperture 17

20 through which a bolt or similar securing means may be passed for supporting the outlet box on a wall or the like. In this instance the disk 16 is first placed in its opening and a bolt or similar fastening means is

25 passed therethrough and the box may thus be secured in any desired position. A plurality of these disks may be provided, no particular number being specified.

From the above description taken in connection with the accompanying drawing, it is thought that a clear and comprehensive understanding of the construction, use, and advantages of my invention may be gathered. It will be noted that when it is desired to use the device, its disposition in desired position may be readily attained, owing to the simplicity of construction and ease with which an electric conduit may be connected thereto, and it will also be noted that 40 the outer appearance of the device will be capable of vast improvement over the pres-

ent devices of this character. It is not thought that a lengthy discourse on the other minor advantages of my invention is necessary at this time, but I desire it to be understood that while I have shown and described my invention as possessing a peculiar form and construction, I may make such changes in the details thereof that do not depart from the spirit and scope of the invention as claimed.

Having thus described my invention what I claim and desire to secure by Letters Patent is:

1. An outlet box, including a casing having a plurality of threaded apertures therein, closures for certain of said apertures, means engageable with certain other of said apertures for attachment therewith of electric conduits of various sizes, apertured members associated with certain of said threaded apertures to facilitate the securement of the device in a desired position.

2. An outlet box including a rectangular casing having an open side and a plurality of threaded apertures in its remaining sides, said casing also having threaded apertures in its end portions, closures for certain of said apertures, means engageable with certain other of said apertures for attachment therewith of electric conduits of various sizes, apertured members associated with certain of said threaded apertures to facilitate the securement of the device to a stationary support.

In testimony whereof I affix my signature in presence of two witnesses.

ARTHUR WILSON BAKER.
